RACKET FOR TABLE TENNIS AND SIMILAR GAMES

Byron C. Schmid, Washington, D. C.

Application April 19, 1938, Serial No. 202,962

16 Claims. (Cl. 273—76)

This invention is an improved racket or bat for use in games, such as table tennis, lawn tennis, squash, badminton, and the like. While the invention is illustrated for table tennis, the structure and functional purpose of the invention may be embodied in rackets for lawn tennis, badminton, squash, and the like.

The usual racket in games of the type here involved, is provided with a straight handle, although some rackets have been proposed where the handle is at an angle with respect to the striking face of the racket, as in the patent to Taylor No. 335,656, of 1886, and the patent to Girdwood No. 703,911, of 1902. According to the present invention, the handle of the racket is angularly and otherwise displaced, in such a way that the longitudinal vertical axis through the striking face of the racket passes substantially through the point about which the wrist of the user pivots. The provision of a handle of this sort gives the racket better balance in the hands of the user, such that it may be quickly controlled and moved from various positions, particularly in changing from the forehand to the backhand, and vice versa. In many strokes, it enables one to hit the ball more squarely, when such is desired.

With certain positions of the forearm, in the case of a right-handed player, the user finds that he can twist the forearm further to the left than to the right. Also, with one's forearm hanging relaxed at one's side, the hand can be turned at the wrist toward the body through a much greater angle than it can be turned in the opposite direction from the initial position. In order to compensate for these factors, the striking face of the racket is angularly offset to the right, so that the right-handed player does not need to turn his forearm and/or wrist quite so far to the right to get the racket well to the right for making a stroke in such position. The ease of making and the resultant accuracy and power of forehand and backhand strokes are, by this invention all improved.

The foregoing principles are structurally embodied in a racket which may take a number of possible forms. In one aspect, the upper end of the handle is offset with respect to the striking face of the racket, this handle, however, being angularly mounted so that its longitudinal axis intersects the plane in which the striking face lies, at a point below the outside of this striking face. This angle may conveniently be about 20° and the point of intersection just mentioned is approximately at or near the lower end of the

handle. This is probably the simplest aspect of the invention.

The handle, in addition to the angular offset just described, may also be provided with another type of offset; the longitudinal axis of the handle which, in this case, is vertical when considered in front view, may be laterally offset with respect to the vertical longitudinal axis of the striking face, so that planes, perpendicular to the striking face and passed through said axes, respectively, would be parallel and separated by an amount corresponding to said offset. The axis of the handle intersects the plane in which the striking face lies, at a point below and outside said striking face, at or near the lower end of the handle.

The invention, in still another aspect, may be provided with a handle which is both angularly and laterally offset, as described above. In addition, however, the longitudinal axis of the handle, when considered in front view, is tipped or slanted with respect to a plane passed through the vertical longitudinal axis of the striking member and perpendicular thereto, so that the axis of the handle intersects that plane at an angle of approximately 15°.

The several types of handles just described may be made variably positionable, so that the handle may be set in different angular adjusted positions with respect to the striking face, to best accommodate the desires of a particular user.

The general features of the invention having been thus described, the invention will now be illustrated in more detail in the accompanying drawings, showing further details of construction and illustrating a number of different embodiments of the invention.

In these drawings:

Figure 1 is a front view of the simplest embodiment of the invention;

Figure 2 is a side view of the same;

Figure 3 is a front view of a modification;

Figure 4 is a side view of the same;

Figure 5 is a perspective view of the form of invention shown in Figures 3 and 4;

Figure 6 is a front view of another modification;

Figure 7 is a side view of the same;

Figure 8 is a perspective view of the same;

Figures 9 and 10 are front and side views, respectively, of another modification;

Figures 11 and 12 are fragmentary front and side views of still another modification;

Figure 13 is a view in side elevation of a detail; and

55

Figure 14 is a fragmentary view in side elevation of certain details permitting various angular settings of the elements.

- Referring now to these drawings, in which 5 similar reference characters indicate similar parts, 2 indicates the striking member or racket face which, in the case of a table tennis racket, is usually covered with a roughened material 4. The longitudinal vertical axis of the striking member is shown at 6. Suitably secured to the lower edge of the striking member 2 is an offset 8, as by bolts 10 passing through a small plate 12 and the upper portion 14 of the offset. The offset 8 extends downwardly and outwardly, as shown in 10 Figure 2, and to the outer end of this offset is secured a handle 16. The angle between the axis 6 of the striking member 2 and the central longitudinal axis 18 of the handle, is approximately 15°, although this angle may be varied. 15
- 20 The axis 18' of the handle intersects the plane in which the striking member 2 lies at the point P, which is below and outside the face of the striking member, and preferably is at or near the lower end of the handle.
- 25 While the connection between the upper end of the handle 16 and the lower edge of the racket is shown as an offset 8, the details of this connection in the various embodiments of the invention, may be varied considerably. For example, the 30 entire article may be built of plywood, which may be steamed to make it flexible, and the connection 8 be made of such plywood. Again, this connection might be made of one of the many available synthetic resins which may be molded readily 35 into the desired shape.
- 35 Referring now to the modification shown in Figures 3, 4 and 5, the handle 16' is connected to the striking member 2 by the offset 8', which gives an angular offset of about 20° between the axis 6' of the striking member and the longitudinal axis 18' of the handle, as described in connection 40 with Figures 1 and 2. The handle 16', however, is also laterally offset with respect to the central vertical longitudinal axis 6' by an amount S, this offset being measured between the central longitudinal axis 6' of the racket and the central longitudinal axis 18' of the handle. To describe 45 this offset in another way, if planes both perpendicular to the face of the striking member 2 are passed respectively through the axes 6' and 18', these planes would be parallel and separated by the distance S.
- 50 Referring now to the modification shown in Figures 6, 7 and 8, which is one of the preferred 55 forms of the invention, the handle 16a is connected to the lower edge of the racket by the offset 8a so that the angle between the longitudinal axes 6a and 18a is about 20°, as before. However, in addition to this offset, the handle 16a has its 60 longitudinal axis 18a extending at an angle as shown in Figure 6, so that a plane passed through the axis 18a, perpendicular to the face of the racket, would intersect the axis 6a of the striking member 2 at about the point 19. When the 65 racket is viewed from the front as in Figure 6, the apparent angle between the axes 6a and 18a is about 15°, although this angle is only apparent because the axes 6a and 18a do not actually intersect. This angle also may be described by stating 70 that if planes perpendicular to the striking face of the racket 2 are passed through the axes 6a and 18a, the actual angle between such planes is about 15°. The axis 18a of the handle intersects the plane in which the face of the racket lies at a 75 point well below the racket at about the point P.

This point P is approximately at the lower end of the handle, but the invention is not limited to the intersection at exactly this point.

Referring now to the modification shown in Figures 9 and 10, the upper end of the handle 16b is connected to the lower edge of the striking member 2 by the angular offset 8b, the upper end of the handle being offset to the right of the central axis 6b of the racket, as distinct from the modifications shown in Figures 3 and 6, where the upper end of the handle is offset to the left of the corresponding axis. The angle between planes, both perpendicular to the striking face of the racket and passed respectively through the axes 6b and 18b is approximately 15°, as shown in 15 Figure 9. The angle between axes 6b and 18b in the side view of the racket is approximately 20°. These angles, however, may be varied, as the invention is not limited to these precise angular values. The offset 8b in Figures 9 and 10, in 20 addition to extending downwardly and forwardly to the right, is also, as viewed in Figure 10, angularly set so that in side elevation one sees part of the top of the offset as distinct from the other views as in Figures 1, 3 and 6, where one sees the 25 edge of the offset. This particular angular arrangement gives somewhat different balance to the racket which may be preferred by some users.

It will be noted in connection with Figures 3, 4, 6, 7, 9 and 10 that the upper end of the handle is 30 in a position to one side of a plane passing through the longitudinal axis of the striking face and perpendicular thereto. It will also be noted that the longitudinal axis of the handle intersects the plane of the striking member at approximately the lower end of the handle. It will still further be noted that the longitudinal axis of the handle and the longitudinal axis of the striking member are lines which are always spaced from one another and never intersect, even if indefinitely prolonged. The apparent intersection of the axes in Figure 6 is not a real intersection, as is evident from Figure 7. The apparent intersection of the axes in Figure 4 is not a real intersection, as is apparent from Figure 3. The apparent intersection of the axes in Figure 9 is not a real intersection as is evident from Figure 10.

Referring now to Figures 11 and 12, the connection between the handle 6 and the striking member 5 of the racket is by means of an offset 50 including a ball and socket joint indicated generally at 22, and including a set screw 24 whereby the angular relationship between the handle and the racket face may be varied as desired and the two held in such angular relationship by the set 55 screw 24, which bears against the ball of the ball and socket joint. Slots 26 may also be provided for a variable setting of the plate 28 connected by bolts or the like to the member 2.

In order to vary the length of any of the offset 60 connections between the handle and the striking member 4, such offset, as shown in Figure 13, may be composed of two relatively slideable plates 30 and 32 which may be variably positioned by bolts 34 passing through suitable slots in the plates, whereby it will be evident that the effective length of the offset may be varied and such length fixed by tightening up on the bolts 34.

Figure 14 shows a modification of the invention 70 providing for a great many possible settings of the handle. In this modification the offset 8c consists of overlapping, relatively adjustable plates 36 and 38, which slide relatively to each other and may be held in any adjustable position by 75

bolts 40 passing through suitable slots in the plates.

One of these plates, such as 38, is provided with a socket member 40 of a ball and socket joint, the ball member 42 of which is carried by the lower edge of the striking member 2, the relative position between the ball and socket members being settable by a set screw 44. The other plate 36 may be provided with a socket member 46 of a ball and socket joint, the ball member 38 of which is carried by the handle 16. This joint may also be set in any position by the set screw 50. The provision of the two ball and sockets just described gives an indefinite number of angular variations between the handle, the offset and the striking face so that a player who may desire a particular angular setting of these parts may, by experiment and use of the set screws, achieve the precise angular setting that is most suitable for him.

It is to be understood, furthermore, that of the three variable settings permitted by the structure of Figure 14, any one or any two, or all three, may be embodied in a particular racket, as desired.

25 In all forms of the invention, the handle, in cross section, has the shape of an elongated polygon, preferably having eight sides. The wider face of the handle, when the racket is viewed from the front, as in Figures 1, 3, 6, etc., is directly 30 toward the observer.

While the invention has been described in some detail, it should be understood that the invention is not limited to these precise details, but may be carried out in other ways.

35 I claim as my invention:

1. A racket for table or lawn tennis, squash, badminton and the like, comprising a striking member and a handle, the upper end of the handle being offset from the lower edge of the striking member, with the upper end of the handle in a position to one side of a plane passing through the longitudinal axis of the striking face and perpendicular thereto, the longitudinal axis of the handle extending at an angle to intersect the 45 plane in which the striking member lies, at a point below and outside the face of the striking member.

2. A racket for table or lawn tennis, squash, badminton and the like, comprising a striking member and a handle, the upper end of the handle being offset from the lower edge of the striking member, with the upper end of the handle in a position to one side of a plane passing through the longitudinal axis of the striking face and perpendicular thereto, the longitudinal axis of the handle extending at an angle such that the plane, in which the striking member lies, intersects the longitudinal axis of the handle approximately at the lower end of the handle.

30 3. A racket for table or lawn tennis, squash, badminton and the like, comprising a striking member and a handle, the upper end of the handle being offset from the lower edge of the striking member, with the upper end of the handle in a 35 position to one side of a plane passing through the longitudinal axis of the striking face and perpendicular thereto, the longitudinal axis of the handle extending at an angle to intersect the plane in which the striking member lies, at a point below and outside the face of the striking member, the angle between said axis and said plane being approximately 20°.

35 4. A racket for table or lawn tennis, squash, badminton and the like, comprising a striking member and a handle, offset means, secured to

the lower edge of the striking member and to the upper end of the handle, said offset means serving to position the handle with its longitudinal axis always spaced from and in non-intersecting relation with the longitudinal axis of the striking member.

5 5. A racket for table or lawn tennis, squash, badminton and the like, comprising a striking member and a handle, offset means, secured to the lower edge of the striking member and to the upper end of the handle, said offset means serving to position the handle with its longitudinal axis always spaced from and in non-intersecting relation with the longitudinal axis of the striking member, said offset means holding the handle 10 with its longitudinal axis extending at an angle to intersect the plane in which the striking member lies, at a point below and outside the face of the striking member, the angle formed by such intersection being about 20°.

20 6. A racket for table or lawn tennis, squash, badminton and the like, comprising a striking member and a handle, offset means, secured to the lower edge of the striking member and to the upper end of the handle, means for varying the effective length of said offset means, said offset means holding the handle with its longitudinal axis extending backwardly at an angle to intersect the plane in which the striking member lies, at a point below and outside the face of the striking member.

25 7. A racket for table or lawn tennis, squash, badminton and the like, comprising a striking member and a handle, offset means, extending laterally and diagonally away from the striking member, secured to the lower edge of the striking member and to the upper edge of the handle, to hold the handle at an angle to intersect the plane in which the striking member lies, at a point below and outside the face of the striking member, said offset 30 serving to position the upper end of the handle to one side of a plane passing through the longitudinal axis of the striking face and perpendicular thereto.

35 8. A racket for table or lawn tennis, squash, badminton and the like, comprising a striking member and a handle, offset means, secured to the lower edge of the striking member and to the upper end of the handle, means for varying the effective length of said offset means, said offset means holding the handle with its longitudinal axis extending backwardly at an angle to intersect the plane in which the striking member lies, at a point below and outside the face of the striking member, the angle formed by such intersection being about 20°.

40 9. A racket for table or lawn tennis, squash, badminton and the like, comprising a striking member and a handle, offset means, extending laterally and diagonally away from the striking member, secured to the lower edge of the striking member and to the upper edge of the handle, to hold the handle at an angle to intersect the plane in which the striking member lies, at a point below and outside the face of the striking member, and means for varying the effective length of said offset means.

45 10. A racket for table or lawn tennis, squash, badminton and the like, comprising a striking member and a handle, offset means, extending laterally and diagonally away from the striking member, secured to the lower edge of the striking member and to the upper edge of the handle, said offset 50 serving to position the upper end of the handle to one side of a plane passing through the 55

longitudinal axis of the striking face and perpendicular thereto, said offset further serving to hold the handle extending diagonally toward the plane in which the striking member lies, such that said plane intersects the handle approximately at the lower end thereof.

11. A racket for table or lawn tennis, squash, badminton and the like, comprising a striking member and a handle, the upper end of the handle being offset from the lower edge of the striking member, so that said upper end is located in a plane to one side of a plane passing through the longitudinal axis of the striking face and perpendicular thereto, the longitudinal axis of the handle extending at an angle to intersect the plane in which the striking member lies, at a point below and outside the face of the striking member, and means for varying the angular setting of the handle.

12. A racket for table or lawn tennis, squash, badminton and the like, comprising a striking member and a handle, the upper end of the handle being offset from the lower edge of the striking member, so that said upper end is located in a plane to one side of a plane passing through the longitudinal axis of the striking face and perpendicular thereto, the longitudinal axis of the handle extending at an angle such that the plane, in which the striking member lies, intersects the longitudinal axis of the handle approximately at the lower end of the handle, and manually settable means for varying the angular relationship between the handle and the striking member.

13. A racket for table or lawn tennis, squash, badminton and the like, comprising a striking member and a handle, offset means, secured to the lower edge of the striking member and to the upper end of the handle, so that said upper end is located in a plane to one side of a plane passing

through the longitudinal axis of the striking face and perpendicular thereto, said offset means also holding the handle with its longitudinal axis extending at an angle to intersect the plane in which the striking member lies, at a point below and outside the face of the striking member, and means, forming a part of said offset means, for varying the angular setting of the handle.

14. A racket for table or lawn tennis, squash, badminton and the like, comprising a striking member and a handle, the upper end of the handle being offset from the lower edge of the striking member, the longitudinal axis of the handle extending downwardly and backwardly at an angle to intersect the plane in which the striking member lies, at a point below and outside the face of the striking member, the handle being so placed that planes, perpendicular to the face of the striking member, and passed respectively through the longitudinal axes of the handle and of the striking member, are substantially parallel, and are spaced apart.

15. A racket for table or lawn tennis, squash, badminton and the like, comprising a striking member and a handle, the upper end of the handle being offset from the lower edge of the striking member, the longitudinal axis of the handle extending downwardly and backwardly at an angle to intersect the plane in which the striking member lies, at a point below and outside the face of the striking member, the handle being placed at an angle so that planes, perpendicular to the face of the striking member and passed respectively through the longitudinal axes of the handle and of the striking member, intersect at an angle.

16. The combination as claimed in claim 15, in which the angle of intersection of the planes is approximately 15°.

BYRON C. SCHMID.
